TREATMENT OF GASOLINE

Vasili I. Komarewsky, Chicago, Ill., assignor to
Universal Oil Products Company, Chicago, Ill.,
a corporation of Delaware

Application January 30, 1939, Serial No. 253,603

17 Claims. (Cl. 196—49)

This invention relates particularly to the treatment of gasolines of inferior knock-rating to improve them in this respect and is specially concerned with a catalytic treating process for accomplishing this object.

While the process to be disclosed is primarily adapted to the treatment of straight-run gasolines produced by the simple distillation of crude oils, it may be also applied under suitably modified conditions of operation to cracked gasolines in conjunction with the cracking process to increase the overall efficiency thereof.

Apart from the small amounts of contaminating compounds containing sulfur, nitrogen, and oxygen which are present in varying amounts in straight-run gasolines, extensive analyses for hydrocarbon groups have shown that straight-run gasolines consist essentially of mixtures of 6-carbon atom naphthalene hydrocarbons and various paraffin hydrocarbons in varying proportions. The group analyses thus far made, do not completely distinguish between naphthalenes of 5, 6, and 7 carbon atoms in the ring or between paraffin hydrocarbons of normal or branched chain structure, but for the purpose of the present description of a process applicable to improving the knock rating of these gasolines, they may be considered as consisting of varying proportions of cyclo-hexane and its alkylated derivatives on the one hand and the various normal paraffin hydrocarbons ranging from approximately 5 to 12 carbon atoms to the molecule on the other hand.

It is a known fact that in general the more highly unsaturated compounds of a given molecular structure have a higher antiknock value than the saturated compounds. It is further known in general that cyclic compounds have a generally higher antiknock value than straight-chain compounds of a similar number of carbon atoms unless the latter are of a branched chain or isomeric structure. The process of the present invention utilizes both of these facts in converting in the most selective and generally advantageous manner substantial proportions of the naphthalene content of gasolines into aromatics and substantial proportions of the paraffin content into olefins and aromatics as will be herein-after more fully disclosed.

In one specific embodiment the present invention comprises a process for improving the anti-knock value of gasolines which comprises first subjecting the gasoline to contact with catalysts effective in dehydrogenating the naphthalenes and then subjecting the gasoline from the first

step to further treatment with catalysts effective in dehydrogenating and producing cyclic compounds from the paraffin hydrocarbons.

It is within the scope of the invention to employ different catalysts in the two stages or to employ the same catalyst with the temperature and other conditions so that the dehydrogenation of the naphthalenes is brought about in the primary stage with substantially no effect on 10 aliphatic hydrocarbons while the said aliphatic hydrocarbons are dehydrogenated and cyclized in the second stage under more severe conditions of operation in regard to temperature and time of contact. This point will be developed in later 15 examples.

The process of the present invention is to some extent based on the fact that the conditions and catalysts best employed for dehydrogenating naphthalenes are sharply differentiated from those 20 which are best for dehydrogenating and cyclizing straight chain hydrocarbons. Whereas catalytic reforming processes are known for improving the antiknock value of gasolines inferior in this respect, substantially all of these processes 25 operate in a single stage with a selected catalyst under average conditions which are found by trial to produce the best overall results but usually not the optimum for the treatment of the different hydrocarbon groups separately. For example, cyclo-hexane and other naphthalenes are readily dehydrogenated to benzol and its alkylated derivatives by contacting their vapors with nickel or other members of the iron group at temperatures of the order of 250-300° C. These 30 conditions, however, are usually without material effect upon paraffin hydrocarbons of gasoline boiling range and if conditions of increasing severity are employed with the same catalysts, the paraffins show a greater tendency to suffer carbon-to-carbon splitting and the formation of undesirably large amounts of gases and heavy liquid 35 byproducts.

As previously intimated, it is within the scope 40 of the invention to use other catalysts than nickel or the other members of the iron group in the first stage and these catalysts may be of a mixed character such as, for example, alumina supporting both nickel and chromium sesquioxide. In 45 the manipulation of the process with such catalysts it is possible to regulate conditions so that substantially only naphthalenes are dehydrogenated in the primary stage, the temperatures usually employed for this being of the order of 350-450° C., depending upon the percentage of naphthalenes 50

present and the activity of the particular catalyst employed.

If catalysts are employed which are primarily effective in dehydrogenating and cyclizing the paraffin and other straight-chain hydrocarbon compounds present in admixture with naphthenes in a given gasoline, the conditions employed are usually too severe for the simple dehydrogenation of naphthenes and the catalysts furthering the reactions of the paraffins are not as specific in their dehydrogenating effect upon naphthenes as the nickel and other materials mentioned. The present invention comprises therefore the step-wise aromatization of gasolines using first combinations of catalysts and conditions specific to the dehydrogenation of naphthenes and secondly those catalysts and conditions which tend to cause dehydrogenation and dehydrocyclization of paraffins.

For the dehydrogenation of naphthenes, nickel, cobalt and iron have already been mentioned, but it is within the scope of the invention to employ if desired more expensive materials such as the members of the platinum group, including platinum, palladium, iridium, osmium, etc. In the operation of the process, best results are usually obtained when these metals are used on relatively inert granular supports to present a larger catalytic surface due to their extensive distribution. Various types of supporting materials of a siliceous or aluminous character may be employed as carriers such as, for example, kieselguhr and other forms of silica, clays, and other silicates, alumina, either natural or prepared and other inert materials. In the treatment of most gasolines with such catalysts, temperatures of approximately 300° C. are employed in the first stage, the gasoline being vaporized and passed over a selected and active dehydrogenating metal catalyst at a rate commensurate with obtaining best results in converting the naphthene content into aromatics. Obviously the exact conditions of operation will be determined by the amount and character of the naphthenes present in whatever gas mixture is being treated.

After the aromatization of the naphthene content, the type of catalyst is changed and the vapors with or without separation of hydrogen and other reaction products are contacted with catalysts which have a dehydrogenating and cyclizing activity with respect to residual paraffin hydrocarbons. Catalysts of this character include generally compounds and particularly oxides of the elements in the left-hand columns of groups 4, 5, and 6 of the periodic table, including titanium, zirconium, cerium, hafnium, thorium, vanadium, columbium, tantalum, chromium, molybdenum, tungsten, and uranium. Such catalysts are readily prepared by depositing nitrates or other salts or hydroxides of the elements on miscellaneous supports and calcining and reducing with hydrogen or hydrocarbons to produce the lower oxides. The optimum percentages of these oxides which are suitable for effecting the desired dehydrogenation and cyclizing of mixtures of paraffin hydrocarbons will obviously vary with the amount and character of the paraffin hydrocarbons and the activity of the particular oxide promoter. However, a few trials will determine which is the most effective in a given instance. Granular activated aluminas prepared from precipitated aluminum hydroxide by calcination methods or by similar treatment of some naturally occurring aluminum

hydroxides or carbonates furnish suitable supports for the catalytic oxides and a catalyst which has given excellent service consists of granular activated alumina supporting minor proportions (usually 15-20% by weight) of chromium sesquioxide. The temperatures employed in the second step are preferably somewhat higher than those employed in the primary stage of the process and are usually 450° C. or higher, this combination of temperature and catalyst being substantially without effect on the aromatic hydrocarbons produced from the first stage.

The accompanying drawing is a flow diagram of the process of my invention. The naphtha charging stock is supplied to the system by way of line 1 from which it is directed to the first dehydrogenating zone indicated by 2 in the drawing. In this zone the hydrocarbons are subjected to contact with a dehydrogenating catalyst under conditions effective in the dehydrogenation of naphthenes to form aromatics. As hereinbefore set forth, the temperature of the catalyst in this stage is of the order of 250-450° C. while utilizing such catalysts as nickel on supporting materials such as kieselguhr or other substances of siliceous or aluminous character. The products of this dehydrogenation zone are removed by way of line 3 and, if desired, may be directed to a separation zone No. 1, indicated by 5 in the drawing. In this separation zone, hydrogen together with smaller quantities of normally gaseous hydrocarbons is removed from the system by way of line 6. If desired, this separation step may be omitted and the reaction products from the first dehydrogenation zone in this case are directed from line 3 to line 4 which connects with line 1, supplying the second dehydrogenation zone indicated by 8 in the drawing. In the second dehydrogenation zone the paraffins are dehydrocyclized to form aromatic hydrocarbons. The temperature in the second zone lies within the approximate limits of 450-750° C. Effective catalysts in the second zone comprise particularly group 5 and group 6 oxides supported on refractory materials such as alumina. Group 4 oxides have also been used but in general are regarded as less effective than such oxides as those of vanadium, chromium and molybdenum. The products from the second dehydrogenation zone are directed by way of line 9 to a second separation zone indicated by 10 in the drawing. In this second separation zone, hydrogen and normally gaseous hydrocarbons are separated from the stabilized gasoline which constitutes the product of the process. It is usually found desirable to rerun the stabilized gasoline in order to reduce the quantity of gum forming constituents present therein.

The following example is given to indicate the advantages of the present type of process in improving the antiknock value of straight run gasolines, although it will be understood that catalysts and conditions will be considerably modified in the case of other gasolines so that the example is not intended to place undue limitations on the scope of the invention.

A Pennsylvania straight run gasoline fraction boiling between 100 and 150° C. and having an octane number by the motor method of 43 was treated by three different procedures as follows:

(1) Vapors were passed over a catalyst consisting of reduced nickel on alumina at a temperature of 300° C. and substantially atmospheric pressure. After this treatment, it was found by

analysis that the percentage of aromatic hydrocarbons was 36.5 and that the octane number has been raised to 51. The gas evolved consisted of 95% hydrogen.

After separation of hydrogen the product of the first stage was passed over an alumina-chromia catalyst at a temperature of 450° C. and analyses indicated that the percentage of aromatics had been increased to 55 and the octane number raised to 75. The gas evolved in the second stage was 92% hydrogen.

(2) A catalyst was prepared which contained both nickel and chromium oxide on alumina and the vapors of the gasoline fraction were passed over this catalyst at a temperature of 450° C. to simulate a one-stage reforming operation. This treatment produced an aromatic content of 45% and raised the octane number to 65. The gas evolved contained 85% hydrogen. It will be seen by this test that poorer results were obtained by combining the catalyst and using a single selected temperature for the reforming operation.

(3) Using an alumina-chromia-nickel catalyst, the vaporized gasoline fraction was treated at 405° C. to increase the aromatic content to 45% and raise the octane number to 57, the gas evolved consisting of 94% hydrogen. In the second stage the products were passed over the same catalyst at 450° C., the yield of products consisting of 60% aromatics and having a 75 octane number, and the gas evolved consisting of 91% hydrogen.

It will be seen from the immediately preceding data that better results were obtained with an alumina-chromia-nickel catalyst when the aromatization of the gasoline was conducted in two stages as in section (3) since the octane number obtained was 75 whereas that obtained in the single-stage treatment under section (2) was only 65.

I claim as my invention:

1. A process for the treatment of gasoline containing naphthenic and aliphatic hydrocarbons to increase the antiknock value thereof which comprises subjecting vapors of said gasoline in a first stage to contact at a temperature of the order of 250-450° C. with a catalyst effective in dehydrogenating naphthenic hydrocarbons and in a second stage to contact at a temperature within the range of 450-750° C. with a catalyst effective in dehydrogenating and cyclicizing aliphatic hydrocarbons.

2. A process for the treatment of straight run gasoline containing naphthenic and aliphatic hydrocarbons to increase the antiknock value thereof which comprises subjecting vapors of said gasoline in a first stage to contact at a temperature of the order of 250-450° C. with a catalyst effective in dehydrogenating naphthenic hydrocarbons and in a second stage to contact at a temperature within the range of 450-750° C. with a catalyst effective in dehydrogenating and cyclicizing aliphatic hydrocarbons.

3. A process for the treatment of cracked gasoline containing naphthenic and aliphatic hydrocarbons to increase the antiknock value thereof which comprises subjecting vapors of said gasoline in a first stage to contact at a temperature of the order of 250-450° C. with a catalyst effective in dehydrogenating naphthenic hydrocarbons and in a second stage to contact at a temperature within the range of 450-750° C. with a catalyst effective in dehydrogenating and cyclicizing aliphatic hydrocarbons.

4. A process for the treatment of gasoline to increase the antiknock value thereof which comprises subjecting vapors of said gasoline in a first stage to contact with a catalyst containing a metal effective in dehydrogenating naphthenes, and in a second stage to contact with a catalyst containing a metal oxide effective in dehydrogenating and cyclicizing paraffins.

5. A process for the treatment of straight run gasoline to increase the antiknock value thereof which comprises subjecting vapors of said gasoline in a first stage to contact with a catalyst containing a metal effective in dehydrogenating naphthenes, and in a second stage to contact with a catalyst containing a metal oxide effective in dehydrogenating and cyclicizing paraffins.

6. A process for the treatment of cracked gasoline to increase the antiknock value thereof which comprises subjecting the vapors of said gasoline in a first stage to contact with a catalyst containing a metal effective in dehydrogenating naphthenes, and in a second stage to contact with a catalyst containing a metal oxide effective in dehydrogenating and cyclicizing paraffins.

7. A process for the treatment of gasoline to increase the antiknock value thereof which comprises subjecting vapors of said gasoline in a first stage to contact at a temperature of the order of 250-350° C. with a catalyst containing a metal effective in dehydrogenating naphthenes, and in a second stage to contact at a temperature of the order of 450-750° C. with a catalyst containing a metal oxide effective in dehydrogenating and cyclicizing paraffins.

8. A process for the treatment of straight run gasoline to increase the antiknock value thereof which comprises subjecting vapors of said gasoline in a first stage to contact at a temperature of the order of 250-350° C. with a catalyst containing a metal effective in dehydrogenating naphthenes, and in a second stage to contact at a temperature of the order of 450-750° C. with a catalyst containing a metal oxide effective in dehydrogenating and cyclicizing paraffins.

9. A process for the treatment of cracked gasoline to increase the antiknock value thereof which comprises subjecting the vapors of said cracked gasoline in a first stage to contact at a temperature of the order of 250-350° C. with a catalyst containing a metal effective in dehydrogenating naphthenes, and in a second stage to contact at a temperature of the order of 450-750° C. with a catalyst containing a metal oxide effective in dehydrogenating and cyclicizing paraffins.

10. A process for the treatment of gasoline to increase the antiknock value thereof which comprises subjecting the vapors of said gasoline in a first stage to contact at a temperature of the order of 250-350° C. with a reduced nickel catalyst effective in dehydrogenating naphthenes, and in a second stage to contact at a temperature of the order of 450-750° C. with a catalyst containing a metal oxide effective in dehydrogenating and cyclicizing paraffins.

11. A process for the treatment of gasoline to increase the antiknock value thereof which comprises subjecting the vapors of said gasoline in a first stage to contact at a temperature of the order of 250-350° C. with a reduced nickel catalyst effective in dehydrogenating naphthenes, and in a second stage to contact at a temperature of the order of 450-750° C. with a catalyst consisting essentially of granular activated alu-

mina supporting chromium sesquioxide effective in dehydrogenating and cyclizing paraffins.

12. A process for the treatment of gasoline to increase the antiknock value thereof which comprises subjecting the vapors of said gasoline in a first stage to contact at a temperature of the order of 250-350° C. with a reduced nickel catalyst effective in dehydrogenating naphthenes, and in a second stage to contact at a temperature of the order of 450-750° C. with a catalyst consisting essentially of granular activated alumina supporting vanadium sesquioxide effective in dehydrogenating and cyclizing paraffins.

13. A process for the treatment of gasoline to increase the antiknock value thereof which comprises subjecting the vapors of said gasoline in a first stage to contact at a temperature of the order of 250-350° C. with a reduced nickel catalyst effective in dehydrogenating naphthenes, and in a second stage to contact at a temperature of the order of 450-750° C. with a catalyst consisting essentially of granular activated alumina supporting molybdenum sesquioxide effective in dehydrogenating and cyclizing paraffins.

14. A process for the treatment of gasoline to increase the antiknock value thereof which comprises subjecting the vapors of said gasoline in a first stage to contact at a temperature of the order of 350-450° C. with a composite catalyst comprising essentially a relatively inert material supporting chromium sesquioxide and reduced nickel to dehydrogenate naphthenes and in a second stage to contact with a separate portion of the same catalyst at a temperature of the order of 450-750° C. to dehydrogenate and 35 cyclize aliphatic hydrocarbons.

15. A process for increasing the anti-knock value of gasoline distillates containing naphthenic and aliphatic hydrocarbons which comprises contacting the distillate with a dehydrogenating catalyst under dehydrogenating conditions selective for the conversion of naphthenes to aromatics, and thereafter subjecting the thus partially aromaticized distillate to catalytic dehydrocyclization to produce further quantities 10 of aromatics from the aliphatic hydrocarbons.

16. A process for increasing the anti-knock value of gasoline distillates containing naphthenic and aliphatic hydrocarbons which comprises contacting the distillate with a dehydrogenating catalyst under dehydrogenating conditions selective for the conversion of naphthenes to aromatics, and thereafter subjecting the thus partially aromaticized distillate to further contact with dehydrogenating catalyst under conditions selective for the dehydrocyclization of 20 aliphatics into aromatics.

17. A process for increasing the anti-knock value of gasoline distillates containing naphthenic and aliphatic hydrocarbons which comprises contacting the distillate with a dehydrogenating catalyst under dehydrogenating conditions selective for the conversion of naphthenes to aromatics, and thereafter subjecting the thus partially aromaticized distillate to further contact with an additional quantity of said dehydrogenating catalyst under conditions selective for the dehydrocyclization of aliphatics into aromatics. 30
